WORKTABLE SUPPORTING LEG

Norman V. Christensen, Fontana, Calif.

Application March 20, 1953, Serial No. 24,141

Term of patent 7 years

(Cl. D33—14)

To all whom it may concern:

Be it known that I, Norman V. Christensen, have invented a new, original, and ornamental Design for a Worktable Supporting Leg, of which the following is a specification, reference being had to the accompanying drawing, forming a part hereof.

Fig. 1 is a top plan view of the leg.

Fig. 2 is a side elevation view of the leg.

Fig. 3 is a front elevation view of the leg.

I claim:

The ornamental design for a worktable supporting leg, as shown.
